H. F. ENGELS.

PANTALOONS.

No. 291,473.

Patented Jan. 1, 1884.

FIG. 1.

ATTEST.

*Geo. T. Smallwood.
J. Henry Kaiser.*

FIG. 2.

INVENTOR.

Hugo F. Engels.

UNITED STATES PATENT OFFICE.

HUGO F. ENGELS, OF DORCHESTER, ASSIGNOR OF ONE-HALF TO GEORGE FERA, OF BOSTON, MASSACHUSETTS.

PANTALOONS.

SPECIFICATION forming part of Letters Patent No. 291,473, dated January 1, 1884.

Application filed July 19, 1883. (No model.)

To all whom it may concern:

Be it known that I, HUGO F. ENGELS, of Dorchester, county of Norfolk, State of Massachusetts, an alien subject of the Emperor of Germany, now resident in the United States, have invented certain new and useful Improvements in Pantaloons; and I hereby declare that the following is a full, clear, and exact description of my improvement, which will enable others to make and use the same.

It is sometimes inconvenient to button and unbutton the tabs or ends of suspenders, as usually attached to pantaloons, especially behind. A lame hand or arm renders it a painful operation; besides, as is well known, the buttons are apt to pull off, and it is exceedingly uncomfortable to have even one button come off and the suspenders fail to sustain the pantaloons. To remedy this evil I dispense with all buttons on the waistband; and my improvement consists in forming extensions or tabs on said waistband, and integral therewith, said tabs being provided with rings, loops, or equivalent devices, to which the hooks or buckles of the suspenders employed may be attached, thus enabling the ready attaching or detaching of the pantaloons and suspending devices at all times and under any circumstances. This is easily and readily done, saves time, does away with buttons, and enables one with a lame hand or arm to do what otherwise could not be done without assistance.

Referring to the drawings, Figure 1 represents a back view of a pair of pantaloons made in accordance with my invention, and Fig. 2 shows the special construction of the waistband employed.

A is the leg and body portion of the pantaloons; B, the independently-formed waistband attached to the same, in the ordinary manner, by stitching; and C and C' C', tabs or upward extensions of the waistband, said tabs being integral or of one and the same piece with the waistband, and being provided at their extremities with rings or equivalent means for attachment with suspending devices.

I am aware of the United States Patent No. 261,599, and make no claim, broadly, to anything therein described or shown.

Having described my invention, what I claim is—

As a new article of manufacture, the pantaloons described and shown, consisting of the body and leg portion A and the waistband B, attached thereto, said waistband being provided with the tabs or upward extensions C and C' C', made in one piece or integral therewith, substantially as and for the purpose specified.

HUGO F. ENGELS.
